CLAIM

The ornamental design for a floor finish applicator, as shown and described.

DESCRIPTION

FIG. 1 is right, front perspective view of a floor finish applicator embodying our new design;

FIG. 2 is a front elevational view thereof;

FIG. 3 is a rear elevational view thereof;

FIG. 4 is a right side elevation view thereof;

FIG. 5 is a left side elevational view thereof;

FIG. 6 is a top plan view thereof; and,

FIG. 7 is a bottom plan view thereof.

The broken line representations of a container in FIGS. 1 and 2 and the broken line representation of a spray applicator in FIG. 2 are for illustration only and forms no part of the claimed design.
